OIL CIRCUIT BREAKER

Christian Aalborg, Wilkinsburg, Pa., assignor to
Westinghouse Electric & Manufacturing Com-
pany, a corporation of Pennsylvania

Application November 17, 1927
Serial No. 233,846

10 Claims. (Cl. 200—150)

My invention relates to circuit interrupters and more particularly to oil-immersed circuit interrupters of large capacities.

One object of my invention is to provide means within the circuit interrupter that shall minimize the stresses on the supporting structure of the forces which frequently accompany the opening of the circuit interrupter.

Another object of my invention is to provide a partition within the circuit interrupter that shall be positioned below the surface of the contained fluid.

A further object of my invention is to provide a partition below the fluid level of a circuit interrupter that shall prevent the said fluid from being thrown upward in a body and that shall therefore result in equal forces being present in all directions when the circuit interrupter is opened.

A still further object of my invention is to provide a partition below the surface of the fluid in a circuit interrupter that shall provide communication with the upper air chamber through small openings and passages, whereby the interior pressure caused by arcs incident to the opening of the load current may be slowly dissipated.

Heretofore difficulty has been experienced in the circuit interrupter art due to the supporting structure becoming strained and loosened by repeated operation. In analyzing the forces present in the circuit interrupter to ascertain the source of these strains, it was found that the pressure present due to the gases formed by the arc incident to opening the circuit interrupter caused the oil to move upward in a body. The reactive force to this movement causing a downward thrust on the bottom of the tank followed by an upward thrust when the said body of oil came in contact with the top cover member.

In practicing my invention, I provide a partition or a secondary cover below the level of the surface of the fluid which prevents the oil from moving upward in a body and results in equal pressures being exerted by the gases in all directions, thus eliminating the alternate downward and upward forces present in circuit interrupters heretofore employed.

Referring to the drawings, Figure 1 is a side view, in section, of a particular embodiment of my invention.

Fig. 2 is a similar view, taken 90° from the view shown in Fig. 1.

My invention comprises, in general, a tank 1 that contains an insulating fluid 2, having a cover member 3 and a partition 4 that is supported by the cover member 3 and immersed in the insulating liquid 2 below the level of the surface of the said liquid.

The tank 1 is supported from the cover mem-

ber 3 by bolts 10 and has a lining 5 cooperating with its inner wall to insulate the arc therefrom. The cover member 3 is also a means for supporting bushings 6 and 7 (Fig. 2) that terminate in contact members 8 and 9, respectively, within the lower part of the tank 1. A lift rod 11 supports, at its lower extremity, a bridging member 12 carrying the separable electrical contacts of the circuit interrupter, the upper end passing through an aperture 13 of the cover member 3. A spring support member 14 is suspended on the lift rod 11 and abuts against a spring 15 that is compressed when the circuit interrupter is closed and is employed to increase the speed of opening of the bridging member 12. The cover member 3 is supported upon a supporting structure 16 and is bolted thereto by bolts 17 and 18. It will thus be seen that the supporting structure 16 is the means for supporting the entire circuit interrupter through the cover member 3.

The partition 4 may be of any shape, and is shown herein in the shape of a dome, of a diameter slightly smaller than that of the inner wall of the tank. Thus there is clearance 19 between the side wall of the partition 4 and the inner wall of the tank 1. An annular ring 20 is welded to the outer edge of the partition 4 and contains apertures 21 located at different intervals on its circumference. The ring increases the length of the passage 19 and forms one means of permitting the oil to pass from the interior of the tank into an upper chamber 22, formed between the partition 4 and the cover 3. Apertures 23 and 24, through which the conductor bushings 6 and 7 pass, are also employed to aid the passage of the liquid into the upper chamber 22.

Assuming the circuit interrupter to be in the closed position with the contact members closed as shown in the drawings, upon the release of the retaining mechanism (not shown) the bridging member 12 is thrust downward into the position shown in dotted lines in Fig. 2, which movement is accelerated by the release of the energy stored in the spring 15. The gases formed by the arc drawn by this movement will create a pressure within the liquid which will be distributed evenly in all directions, to be slowly dissipated by the passage of the gas and some of the oil through the apertures 22, 23 and 24. The tank structure, the cover, and the bolts are designed of sufficient strength to stand the maximum pressure that may be present within the confined space. The distances between the separable contacts and the bottom of tank 1 and between those contacts and the partition 4, may be made such that the pressure wave, emanating from the arcs at the contacts, impacts simultaneously upon the partition and tank bottom, in consequence of which the two impacts neutralize and produce no net force external to the tank. For this reason, the parti-

tion 4 may well be, in shape, the geometrical image of the tank bottom.

It will thus be seen that I have been able to eliminate the stresses in the supporting structure 5 of a circuit interrupter by preventing the movement of the oil upward in a body against the cover member, thereby preventing a downward thrust of the tank 1 followed by an upward whip that heretofore stressed the anchor bolts of the 10 supporting structure, and the supporting arms of the cover member supported thereto.

It is to be further noted that while this design does not decrease the amount of force present 15 between the tank and the cover member, less damage is likely to result as a result of eliminating the shock that was heretofore present when the body of oil struck the cover member.

It is to be understood that such changes in 20 the form, arrangement and connection of the component parts of my invention may be made as shall fall within the scope of the appended 25 claims.

I claim as my invention:

1. The combination with a tank containing a 25 quenching liquid, of a cover therefor, a partition substantially parallel to the cover and rigidly suspended therefrom below the surface of the liquid, and an annular wall on the partition forming a tortuous path for the liquid between it 30 and the said tank.

2. The combination with a tank having a bottom of substantially dome shape and containing a quenching liquid, of a cover therefor, and a member of a shape similar to that of the said bottom but inverted relative thereto and rigidly suspended 35 below the surface of the said liquid.

3. The combination with a tank containing a quenching fluid and separable contacts, of a cover member for supporting the said tank and contacts, including a concave member positioned 40 below the level of the surface of the said fluid and constituting substantially the geometrical image of the tank bottom.

4. The combination with a tank for enclosing 45 separable contact members of a circuit interrupter, of a quenching fluid therefor contained within the tank, and a curved partition within the tank in opposed relation with the tank bottom and constituting the geometrical image thereof and positioned below the surface of the said liquid above the contact members.

5. In a switch mechanism having a tank containing a quenching fluid and separable contact members wherein large pressures are present 55 when the contact members are separated, a supporting structure for the said tank and means comprising a partition within the tank positioned below the surface of the fluid in such a manner that the contact members are substantially midway between the partition and the bottom of the tank to equalize the stresses produced by the said interior pressure.

6. A circuit interrupter including a housing having a cover and containing an insulating liquid, separable contact members immersed in 65 said liquid and enclosed in said housing wherein large pressures are developed upon circuit interruption, a supporting structure for said housing, a partition carried by the cover of the housing and disposed above the contacts and below the surface of the liquid, and means for opposing the downward force on the bottom of the housing, imposed by said liquid upon circuit interruption,

by the upward force of said liquid on said partition, said means including the cover, the housing, and means connecting the cover to the housing through which said forces are transmitted and imposed against each other, whereby stresses transmitted to the supporting structure upon circuit interruption are minimized. 80

7. A circuit interrupter comprising a housing having a cover and containing an insulating liquid, means for securing the housing and the cover together, separable contact members immersed in the liquid within said housing, a supporting structure for the housing, and means for applying the upward force of the liquid above the contact members, developed upon circuit interruption, to the bottom of the tank to neutralize the downward force of the liquid thereon, said means including a partition carried by the cover and disposed below the surface of the liquid and above the contact members, the upward force being transmitted from said partition through the cover, the securing means and the housing to the bottom thereof to neutralize the downward force thereon, whereby stresses imposed on the supporting structure upon circuit interruption 90 are minimized. 95

8. A circuit interrupter comprising a housing having a cover and containing an insulating liquid, means for securing the housing and the cover together, separable contact members immersed in the liquid within said housing, a supporting structure for the housing, and means for applying the upward force on the liquid above the contact members, imposed thereon upon circuit interruption, to the bottom of the housing 105 to neutralize the force of the liquid thereon, said means including a partition disposed below the level of the liquid and above the contacts, the securing means and the housing through which said forces are transmitted and imposed against each other, whereby stresses imposed on the supporting structure during circuit interruption are minimized. 110

9. A circuit interrupter including separable contact members immersed in a fluid and enclosed in a housing wherein large pressures are developed upon circuit interruption, a supporting structure for said housing and means including a rigidly supported partition within the housing positioned below the surface of the fluid in 120 such relation to said contact members that the pressure transmitted in an upward direction through the liquid is opposed by said partition, and a force is exerted on the housing in opposition to the downward force exerted on the bottom thereof and the stresses exerted upon the supporting structure are thereby neutralized. 125

10. A circuit interrupter comprising a tank containing a quenching liquid, a cover for the tank, bolts securing the cover and tank, separable contact members in said tank, a partition carried by the cover and disposed below and substantially parallel to the surface of the liquid, said liquid developing a high pressure when decomposed by an arc drawn between said contact members which is imposed upwardly on the partition and downwardly on the tank bottom, and means including said cover and said bolts for transmitting the upward force of said pressure on the partition through said cover and said bolts to the tank bottom to neutralize the downward force thereon. 130 140 145
